UNITED STATES PATENT OFFICE.

MICHAEL J. COONEY, OF FORBESTOWN, CALIFORNIA.

SUN-SHIELD.

1,322,544.

Specification of Letters Patent. Patented Nov. 25, 1919.

Application filed February 6, 1918. Serial No. 215,694.

To all whom it may concern:

Be it known that I, MICHAEL J. COONEY, a citizen of the United States, residing at Forbestown, in the county of Butte and State of California, have invented certain new and useful Improvements in Sun-Shields, of which the following is a specification.

This invention relates to sun shields and has for its object the production of a simple and efficient sun shield which may be readily attached to a hat for the purpose of shielding the head of the wearer.

Another object of this invention is the production of a simple and efficient sun shield which may be conveniently adjusted upon hats of various sizes.

With these and other objects in view this invention consists of certain novel constructions, combinations and arrangements of parts as will be hereinafter fully described and claimed.

In the drawings:

Figure 1 is a top plan view of the sun shield,

Fig. 2 is a section taken on line 2—2 of Fig. 1,

Fig. 3 is a top plan view of the modified form of the expandable end of the sun shield section.

By referring to the drawings, it will be seen that the sun shield comprises three different sections indicated in general by the letters A, B and C. Each of these sections comprises an inner band 1 and an outer band 2, the inner and outer bands being connected together by means of the transversely extending strand 3 as clearly illustrated in Fig. 1 of the drawing. The transversely extending strands 3 of the sections B and C are hingedly connected at the point of contact with the transversely extending strand 3 of the section A by means of a suitable spring hinge 8. Each spring hinge 8 is provided with a projecting end 9 for engaging the outer band 2 of one of the sections of the sun shield and in this way normally holds the sections in substantially the same horizontal plane. A strap or band 10 is secured to

the hat pad 5 as shown in Figs. 1 and 2 of the drawings and this strap is provided with an adjusting buckle 11 for the purpose of permitting the strap to be adjusted to a suitable size for fitting conveniently over the crown of a hat or other suitable head covering. The inner band 1 and outer band 2

of each section is braced by means of the radiating braces 4 interposed between the inner and outer bands as clearly shown in Fig. 1 of the drawing, these braces constituting efficient means for holding the inner and outer bands in their proper spaced relation.

A hat engaging band or pad 5 is secured to the inner face of the inner band 1 of each section, and these bands or pads are adapted to fit snugly around the crown of a hat or other suitable head covering for facilitating the holding of the shield upon the hat. Suitable spurs 6' are carried by the pads 5 and extend diagonally therefrom for the purpose of engaging the crown of a hat and firmly holding the shield in engagement therewith.

As shown in Fig. 1, each section of the sun shield constitutes a segment of a circle for producing a substantially circular shield when the sections are assembled. The abutting ends of the sections B and C overlap as clearly illustrated in Fig. 1 and a guiding rod 17 having suitable eyes 18 formed at the respective ends thereof is carried by the overlapping ends of the sections B and C. These eyes 18 receive the inner and outer bands 1 and 2 of the sections B and C as clearly illustrated in Fig. 1 and constitute a guide for the inner and outer bands as the sections B and C are moved toward or away from each other in order to accommodate the sun shield to the crown of a hat or other suitable head covering adapted to support the same. Furthermore, it should be understood that the guiding rod 17 will limit the expansion of the sections B and C with respect to each other.

As will be obvious by considering Fig. 1, a suitable covering 6 is fitted over the frame of the sun shield, which frame is preferably formed of a wire framework and the edges of the covering 6 are rolled or stitched over the inner and outer bands in any suitable or convenient manner for the purpose of firmly holding the covering 6 in engagement with the frame of the sun shield.

In Fig. 3 there is shown a modified form of the means for limiting the expanding movement of the sun shield section, wherein these overlapping portions comprise outwardly extending arms 14. Each arm 14 is provided with an overlapping finger 15. Each finger 15 is provided with an eye 16 at

its outer end, this eye 16 of one finger extending over the other finger as shown in Fig. 3, for the purpose of permitting the arms 14 to be drawn together or moved apart 5 to permit the adjustment of the sections. The cover 6 is of course secured at its outer end to the arms 14 to permit the overlapping fingers 15 to conveniently shield the head of the wearer, and prevent the rays of sun from 10 passing through or between the expandible portions of the shield.

From the foregoing description, it will be seen that a very simple and efficient sun shield has been produced which may be conveniently and readily attached to the hat or other suitable head covering. Furthermore, it will be seen that a very efficient device has been produced, which will also be light in construction and will not have any additional weight to the head of the wearer. The device of course, may be made of any suitable size for the purpose of extending from the crown of the hat in a lateral direction and in this way shield the head of the 25 wearer in a most efficient manner.

It of course should be understood that certain obvious detail mechanical changes may be made in the present device without departing from the spirit of the invention, so long 30 as these changes fall within the scope of the appended claims.

What is claimed is:

1. A sun shield of the class described comprising a plurality of substantially similarly constructed sections, a hat engaging means secured to the inner face of said sections, and spurs carried by said hat engaging means for securing said hat engaging means to a support.
2. A sun shield of the class described comprising a plurality of substantially similarly constructed sections, each section comprising an inner band and an outer band, a hat engaging means secured to the inner band of the sections, means carried by said hat engaging means for securing the sections to a support, a supporting strap secured to one section, adjustable means carried by said strap, and means for connecting said sections together.
3. A sun shield of the class described comprising a plurality of substantially similarly constructed sections, two of said sections be-

ing provided with overlapping portions, means carried by said overlapping portions 55 for limiting the expandible movement of said overlapping portions, and a covering for said sections.

4. A sun shield of the class described comprising a plurality of substantially similarly constructed sections, said sections comprising an inner band and an outer band, some of said sections provided with overlapping portions, each overlapping portion provided with projecting overlapping fingers, each finger provided with an engaging eye at the extremity thereof, the engaging eye of one finger fitting over the other finger, and constituting a means for limiting the expandible movement thereof.

5. A sun shield of the class described comprising a plurality of substantially similarly constructed sections, a hat engaging means carried by each section, means for hingedly connecting some of said sections together, 75 means for normally holding said sections in a contracted position, said sections adapted to be extended for fitting around a hat, and said sections being expandible relative to each other for permitting the same to be adjusted to a suitable size for fitting over a head covering.

6. A sun shield of the class described comprising a plurality of substantially similarly constructed sections, and spring means 85 hingedly connecting some of said sections together and adapted to normally swing said sections to a folded position when said sections are released from engagement with a supporting object.

7. A sun shield of the class described comprising a plurality of substantially segmental sections, some of said sections abutting at their adjoining ends, coil springs connecting said last mentioned sections together and constituting journals therefor, and said coil springs adapted to bring said last mentioned sections into folded relation when said last mentioned sections are released from a supporting medium.

In testimony whereof I affix my signature in presence of two witnesses.

MICHAEL J. COONEY.
